UNITED STATES PATENT OFFICE.

CHARLES B. STRUBLE, OF MINNEAPOLIS, MINNESOTA.

PHOTOGRAPHIC-PRINTING DEVICE.

Application filed December 6, 1920. Serial No. 428,810.

To all whom it may concern:

Be it known that I, CHARLES B. STRUBLE, am a citizen of the United States, residing at Minneapolis, in the county of Hennepin 5 and State of Minnesota, have invented certain new and useful Improvements in Photographic-Printing Devices; and I do hereby declare the following to be a full, clear, and exact description of the invention, such as 10 will enable others skilled in the art to which it appertains to make and use the same.

My invention has for its object to provide an improved photographic printing device especially adapted for use in producing 15 photographic prints by projection either in enlarged or reduced sizes; and to such ends, generally stated, the invention consists of the novel devices and combinations of devices hereinafter described and defined in 20 the claims.

The device comprises a suitable upright support usually and herein designated as an easel, and a printing frame that is detachably and pivotally connected thereto. The 25 detachable feature makes it possible to interchangeably use a plurality of frames, of the same or of different character, in connection with the common easel, and the pivotal connection permits a frame to be turned and 30 set with its longest dimensions either vertical or horizontal. Also, the pivotal connection permits the frame to be set more or less oblique to a vertical or horizontal position so as to bring the sensitized printing 35 paper into parallelism in respect to the negative, when the negative is not set in a true vertical or true horizontal position, as the case may be. The invention also involves certain other novel features, as will herein- 40 after appear.

In the accompanying drawings, which illustrate the invention, like characters indicate like parts throughout the several views.

Referring to the drawings:

Fig. 1 is a front elevation showing the improved printing device;

Fig. 2 is a plan view thereof;

Fig. 3 is a vertical section on the line 3—3 of Fig. 1;

Fig. 4 is a front elevation showing a some- 50 what modified form of printing frame;

Fig. 5 is a top view thereof; and

Fig. 6 is a section on the line 6—6 of Fig. 4.

The easel, as shown and preferably constructed, comprises upright bars 7 supported by feet 8 and rigidly connected by transverse tie bars 9 and 10. The upper and lower tie bars 9 are flush with the upright bars 7, while the intermediate tie bar 10 is 60 secured on the rear edges of said bar 7.

Connected to the lower tie bar 9, by hinges 11, is an arm 12 that extends upward past the intermediate bar 10 and, at the front face of its free end, has a rigidly secured 65 socket plate 13 formed with an approximately V-shaped notch 14, back of which said arm 12 is recessed or cut away at 15. The numeral 16 indicates a clamping bolt that is passed through the upright end of the 70 arm 12 and through the tie bar 10 and is provided, at its rear end, with a thumb nut 17, the head of said bolt being within the recess 15. A leaf spring 18 is anchored at its lower end to the arm 12 and, at its free 75 end, bears against the tie bar 19 and yieldingly presses the arm 12 forward.

The printing frame shown in Figs. 1, 2 and 3 is indicated as an entirety by the numeral 19 and it is provided on its longitudinal edges with retaining ribs or strips 20, the inner edges of which are spaced from the back plate of said frame so that they will overlap and retain the longitudinal edges of a sensitized sheet of printing paper y. 85 A third margin strip 21 is secured to the lower ends of the strips 20 and thus spaced outward slightly from the back plate of the frame. Pivoted at 22, to the inner side of the strip 21, is an adjustable stop 23 which also 90 serves an additional function presently to be described.

A fourth margin strip 24 is pivoted to the upper end of one of the strips 20, and, at its free end, works in the guide yoke 25 applied 95 to the upper end of the other strip 20. This strip 24 is spaced from the back plate of the frame far enough to permit the sensitized

sheet y and also a mask, if desired, to be inserted under the same and under the edges of the strips 20 and under the strip 21 so that the photographic print will be given a white marginal edge, even when the mask is not used. A light coiled spring 26, attached to the free end of the strip 24 and to the upper portion of one of the strips 20, normally yieldingly holds the free end of said strip 24 against one extremity of the yoke 25. As shown, the back plate of the frame 19 is cut away at 27 and the central portion of the pivoted strip 24 is cut away at 28 so as to facilitate positioning and removal of the sheet y .

The central cross bar 19^a of the printing frame 19, at its center, is provided with a headed stud 29 shown as afforded by a screw. This headed stud is adapted to be inserted 20 into the socket afforded by the forked plate 13 and its notch 14, and when so engaged, will afford a pivot on which the printing frame may be rotated from vertical to horizontal positions or any other positions desired. When said stud is thus engaged by the plate 13 and the nut 17, on the bolt 16, is tightened, the socket arm 12 will be moved rearward, carrying with it the plate 13 and causing the latter to pull on the stud 29 and thereby cause the back of the printing frame to be frictionally clamped against the face of the easel. Thus, the frame may be clamped in any desired position. It may be set in a true vertical position or in a true 30 horizontal position and, as the negative is slightly out of true vertical or horizontal position, the printing frame may be moved correspondingly into parallelism therewith so that the image will be printed on the sensitized paper y and properly positioned in respect to the edges thereof.

When the nut 17 is loosened, the spring 18 will move the arm 12 forward, thereby releasing the printing frame from clamping 45 contact with the easel and permitting the same to be readily moved from the notched plate 13. Hence, as is evident, a plurality of printing frames may be interchangeably used on the easel and may 50 be quickly applied to or removed therefrom.

In the form of printing frame shown in Figs. 1, 2 and 3, the margin strip 24 may be pressed forward when desired so as to permit the adjacent edge of the sheet or paper 55 y to be engaged by a finger and thumb for the purpose of removing the same from the frame. Moreover, by giving the pivoted stop 23 a quick inward movement against the paper sheet y , the latter may be projected from the frame beyond the margin strip 24 so that they may be engaged and its removal from the frame completed.

The printing frame shown in Figs. 4, 5 and 6 differs in the frame described in that 60 the cross bar 24^a, which corresponds to the

cross bar 24 of the first described frame, is a fixed bar. Also, this frame, back of the fixed side margin strips 20, is provided with parallel guide channels, one for the sensitized paper sheet y and the other for a mask 70 or vignetting frame y^1 , (see Figs. 5 and 6).

For kicking or projecting the sheet y partly out of the printing frame, I provide a slide 30 mounted in one side of the frame and provided at one end with a thin ejecting finger 31 that is engageable with the adjacent edge of said sheet y . At its other end, the slide 30 has a flat portion 30^a provided at the top of the frame 19 with a finger piece or lug 30^b. The numeral 32 indicates a light coiled spring anchored to one side of the frame 19 and attached at its other end to the slide 30 and normally holding said slide in its inoperative position shown in Fig. 6, with the inner end of the body portion 30^a engaged with the transverse cross bar 10 of the frame. This cross bar 10, like that of the first described frame, has a headed stud 29 for engagement with the notch 14 of the socket plate 13.

After the image has been printed on the sheet y , it is adapted to be partly projected from the frame by engaging a finger with the lug 30^b and thereby pulling the slide 30 upward or against the tension of the spring 32.

As is evident, either one of the two types of frames or any similar frames, may be applied, at will, to the easel in the manner described in connection with the construction 100 illustrated in Figs. 1, 2 and 3. This affords means for quickly and conveniently printing by the use of a plurality of frames and it also provides means for accomplishing all of the required adjustments in doing high 105 grade work. Moreover, the construction described is simple and of small cost.

What I claim is:

1. The combination with an easel having an open socket and means for moving the same rearward, of a printing frame adapted to bear against said easel and having a headed pivot stud detachably engageable with said socket and co-operating therewith to pivotally support said frame and to clamp 115 the same against said easel.

2. The combination with an easel having an open socket and means for moving the same rearward, of a printing frame adapted to bear against said easel and having a headed pivot stud detachably engageable with said socket and co-operating therewith to pivotally support said frame and to clamp 120 the same against said easel, and a nut-equipped bolt for positively drawing said socket rearward.

3. The combination with an easel having an open socket and means for moving the same rearward, of a printing frame adapted to bear against said easel and having a 125

headed pivot stud detachably engageable with said socket and cooperating therewith to pivotally support said frame and to clamp the same against said easel, a nut-
equipped bolt for positively drawing said socket rearward, and a spring tending to press said socket forward.

4. A photo printing frame having a movable print-retaining margin strip yieldingly pressed outward and normally held in working position but adapted to be pressed inward to afford access to the print.

In testimony whereof I affix my signature.

CHARLES B. STRUBLE.
